UNITED STATES PATENT OFFICE.

HORACE M. REESE, OF ATLANTA, GEORGIA.

COTTON-PICKER.

1,241,280.

Specification of Letters Patent. Patented Sept. 25, 1917.

Application filed June 30, 1916. Serial No. 106,837.

To all whom it may concern:

Be it known that I, HORACE M. REESE, a citizen of the United States, residing at Atlanta, in the county of Fulton and State of Georgia, have invented certain new and useful Improvements in Cotton-Pickers, of which the following is a specification.

This invention contemplates an improved cotton picker of the pneumatic type and has as its primary object to provide a device of this character which may be connected to and operated from an ordinary riding saddle.

The invention has as a further object to provide a device of this character wherein when the saddle is in position upon a draft animal, the animal may be ridden between contiguous rows of cotton for transporting the device, and wherein the device will be adapted for operation upon each of said rows.

A still further object of the invention is to provide a device of this character employing a suction fan, and to provide in connection therewith, an efficient mounting for the fan, as well as efficient means for propelling the fan.

And the invention has as a still further object to provide a device of this character wherein cotton will be deposited within suitable sacks or other containers and wherein the said sacks or containers may be readily attached to or detached from the device, so that when one sack becomes filled, it may be readily replaced by an empty sack.

Other and incidental objects will appear as the description proceeds and in the drawings, wherein I have illustrated the preferred embodiment of the invention and wherein similar reference characters designate corresponding parts throughout the several views.

Figure 1 is a side elevation particularly showing the manner in which my improved device is mounted upon a riding saddle, the riding saddle being conventionally illustrated,

Fig. 2 is a front elevation particularly showing the arrangement of the intake tubes of the device when supported in operative position upon a draft animal; this view also showing the arrangement of the discharge nozzle and the locking ring arranged to coöperate therewith for connecting a sack to the said nozzle,

Fig. 3 is a section taken on the line 3—3 of Fig. 2 showing the device detached and more particularly illustrating the internal construction of the picker,

Fig. 4 is a section taken on the line 4—4 of Fig. 3 and particularly illustrating the mounting of the gearing shafts arranged to actuate the suction fan,

Fig. 5 is a fragmentary sectional view particularly showing the thrust bearing provided for the fan shaft, and

Fig. 6 is a fragmentary perspective view of the frame of the picker.

In carrying out my invention, I employ a base 10 which, upon its lower edge is provided with an attaching flange 11 having suitable openings formed therein adapted to receive bolts or other suitable fastening devices by which the said base may be connected to the bow of a saddle in the manner shown in Fig. 1 of the drawings. The saddle shown in this figure has, for convenience, been conventionally illustrated and the bow of the said saddle is cut away or flattened to receive the flange 11, with the bolts connecting the base with the saddle extending through the bow. It will be observed that the base 10 is relatively flat and is arranged in longitudinal relation to the saddle.

Integrally formed on the upper edge of the base 10 is a longitudinally disposed cylindrical casing 12 which is open at its ends and which, upon the upper side thereof, is provided with an opening 13. Formed on the forward edge of the base 10 and integral with the said casing, is a preferably cylindrical flange or head 14, while a frame 15 rises from the casing 12 and extends obliquely and laterally from the base 10 in the manner best shown in Fig. 3 of the drawings. The frame 15 is preferably of the general contour illustrated and is connected to the casing 12 adjacent the extremities thereof, as more particularly shown in Fig. 6, the forward edge of the said frame being integral with the head 14. In this connection, it is to be observed that the said frame lies in a plane with the base 10.

Detachably fitting within the casing 12 is a longitudinally arranged fan shaft 16 which projects through a suitable opening formed in the head 14 and which, adjacent its forward extremity, is supported by anti-friction bearings 17. The shaft 16

adjacent its rear extremity, is provided with an annular groove 18 as shown in detail in Fig. 5 of the drawings adapted to receive anti-friction devices 19 which are removably fitted within a suitable raceway 20, surrounding the opening formed in the adjacent end of the casing 10 and receiving the shaft. Closing the said opening and adapted to maintain the anti-friction devices 19 in operative position, is a plate 21 which is detachably connected to the casing 12 preferably by a plurality of screws 22. It will be seen that the bearing thus provided will operatively support any longitudinal thrust upon the shaft 16.

Mounted upon the opposite side edges of the frame 15 are coacting closure plates 23 which are detachably connected to the said frame by a plurality of bolts or other suitable fastening devices 24. The plates 23 in connection with the frame 15 provide a housing for a train of gears mounted upon parallel shafts 25, 26 and 27, respectively. The plates 23 as best shown in Fig. 4, are, at suitable points, provided with sockets 28 adapted to receive the extremities of the said shafts and arranged within the sockets are anti-frictional devices 29 rotatably supporting the shafts, the said anti-friction devices being mounted within suitable annular raceways formed in the sockets.

The sockets 28 receiving the shaft 25 are open at their outer ends, and the said shaft is arranged to extend therethrough to project laterally upon opposite sides of the gear casing previously referred to. Connected to the projecting outer ends of the shaft 25 are cranks 30, which are provided with handles 31, one of the said cranks being arranged upon each side of the gear casing. It will be noted that the gear casing projects longitudinally of the saddle supporting the device, as shown in Figure 1 of the drawings, toward the rear end of the saddle in such manner that a person sitting upon the saddle may readily operate the cranks 30 to rotate the shaft 25.

Mounted upon the shaft 25 is a gear wheel 32 which is arranged to mesh with a pinion 33 carried by the shaft 26. Mounted upon the shaft 26 is a gear wheel 34 which is arranged to mesh with a pinion 35 carried by the shaft 27. The shaft 27 also has arranged thereon, a gear wheel 36 which is disposed to project through the opening 13 formed in the casing to operatively engage a worm 37 keyed upon the fan shaft 16.

It will now be clear that when the shaft 25 is rotated through the medium of the cranks 30, rotary movement will be imparted to the shaft 16 through the intermediate train of gears. The ratio of these gears will be such as found most desirable in the practical use of the device but pref-

erably, the shaft 16 will be rotated at a relatively high rate of speed, while the shaft 25 is turned but slowly.

Keyed upon the forward end of the shaft 16 is a suction fan 38 which is surrounded by a casing 39. The casing 39 is arranged to seat against the head 14 in the manner best shown in Fig. 3 of the drawings and is detachably connected thereto by a plurality of bolts 40, it being observed that the said casing is formed in sections having coacting flanges 41 formed thereon which are joined by a plurality of bolts 42 detachably connecting the sections of the casing.

The casing 39 upon one side thereof, is extended to provide a tubular discharge spout 43, best shown in Fig. 2 of the drawings and detachably connected to this spout, is a discharge nozzle 44. The discharge nozzle 44 is preferably formed with a substantially frusto-conical outer terminal 45 which merges into a neck 46, the neck being suitably connected with the discharge spout 43. Loosely surrounding the neck 46 of the discharge nozzle and adapted to coöperate therewith, is a locking ring or member 47.

The locking ring 47 is preferably formed from a length of suitable resilient wire and is freely mounted upon the neck 46 of the discharge nozzle to slide longitudinally thereon. Upon one side of the said ring, the length of wire is bent into substantially U-shape to form a laterally projecting ear or hook 48 which may be readily grasped for moving the ring longitudinally upon the neck 46.

In use, the outer frusto-conical terminal 45 of the discharge nozzle is designed to be inserted within the open end of an ordinary cotton sack or other suitable container, and the free edges of the sack will then be folded about the neck 46 of the discharge nozzle. The locking ring 47 will then be arranged to surround such folded portion of the sack and will then be moved to yieldably bind the sack therebetween and the longitudinally tapered neck of the discharge nozzle. It will be observed that the inner terminal 45 of the discharge nozzle will, in use, be adapted to maintain the open end of the sack extended, so that cotton may readily enter the sack while, when one sack has become filled, such sack may be readily detached from the discharge nozzle and a new empty sack easily substituted therefor.

The outer wall of the casing 39, at a point axially of the flange 38 is provided with a suitable opening which is surrounded by the inner terminal 49 of a tubular picking element. The terminal 49 is provided at its inner end with a flange seating against the casing to be detachably connected thereto by a plurality of bolts or other suitable fastening devices 50 and at its outer extremity, is

bifurcated to receive flexible legs 51 adapted, when the device is mounted upon a draft animal, as previously described, to extend upon each side of the said animal in the 5 manner shown in Fig. 2 of the drawings.

The legs 51 may be of any desired length and detachably connected to the outer terminals thereof in any suitable manner, are 10 picker nozzles 52 having angularly disposed terminals 53. Pivots connected to the nozzles 52 are caps 54 which are adapted to be maintained in normal position closing the outer open ends of the said nozzles by spring catches 55 carried by the said caps 15 and adapted to coöperate with suitable lugs formed on the nozzles. The caps 54 will prevent foreign matter from being drawn into the picker element when the nozzles 52 are not actually being used.

From the preceding description, it will thus be seen that when my improved device is mounted upon a draft animal, the said animal may be directed between contiguous rows of cotton, with the picker nozzles 53 so disposed that the cotton from each of said rows may be picked therefrom. A person riding the draft animal and sitting upon the saddle supporting the device will operate the cranks 30 causing a suction to be set 30 up within the fan casing 39 through the medium of the fan 38. Other persons walking upon the ground will then each operate one of the nozzles 53 in the well known manner, to pick the cotton. The cotton, as will 35 be clear, will be drawn up through the picking element 49 into the casing 39 when it will then be discharged through the discharge spout 44 into the sack arranged thereon. It will consequently be seen that 40 I provide a very simple and efficient construction for the purpose set forth.

Having thus described my invention, what I claim and desire to secure by Letters Patent is:

1. A cotton picker for attachment to a riding saddle including a base, means connecting the base with the bow of the saddle, a fan mounted upon the base, a casing surrounding said fan and provided with a dis-

charge opening, a picker element leading 50 into the casing, a gear casing extending from the base rearwardly over the seat of the saddle, and means for rotating the fan and arranged within the gear casing, said means including a drive shaft carried by the 55 gear casing, and a crank mounted upon the shaft and arranged for actuation by an operator seated upon the saddle.

2. A cotton picker for attachment to a riding saddle including a flanged base having a flat lower terminal seating upon the bow of the saddle, means extending through said flanges and connecting the base with the bow, a fan, means for rotating the fan, a casing surrounding the fan and provided 60 with a discharge opening, and a picker element leading into the fan casing.

3. A cotton picker for attachment to a riding saddle including a base formed to seat upon the saddle bow, means connecting 70 the base with the bow of the saddle, a fan mounted upon the base, means for rotating the fan, a casing surrounding the fan and provided with a discharge opening, and a picker element leading into the casing, the 75 said picker element including a bifurcated inner terminal secured to the casing with its furcations projecting laterally in opposite directions with respect to the saddle, and flexible terminals secured to the said 80 furcations.

4. A cotton picker adapted for attachment to a riding saddle and including a base formed to seat upon the saddle bow, means connecting the base with the bow of the saddle, a fan rotatable upon the base, a gear casing projecting from the base rearwardly over the seat of the saddle, means upon the outer extremity of said casing and arranged above the saddle seat for rotating the said 85 fan, a casing surrounding the fan, and a picker element leading into the said casing.

In testimony whereof I affix my signature in presence of two witnesses.
